United States Patent Office

Des. 206,613
Patented Jan. 3, 1967

206,613

METAL DETECTOR

Robert S. Penland, Jr., 405 Elder St.,
Northfield, N.J. 08225

Filed June 3, 1965, Ser. No. 85,558

Term of patent 14 years

(Cl. D52—6)

FIGURE 4

FIGURE 5

FIGURE 1 is an elevational view taken from the front and showing a metal detector embodying my new design;

FIGURE 2 is an elevational view taken from the right side;

FIGURE 3 is an elevational view taken from the rear;

FIGURE 4 is an elevational view taken from the left side; and

FIGURE 5 is a top plan view.

The dominant features of my new design reside in the portions shown in solid lines.

I claim:

The ornamental design for a metal detector, as shown and described.
